MARKER

Leroy Shuger, Baltimore, Md., and Gilbert Rodli, Huntingdon, Pa.; said Rodli assignor, by mesne assignments, to Prismo Holding Corporation, a corporation of New York

Application May 19, 1939, Serial No. 274,667

2 Claims. (Cl. 94—1.5)

This invention relates to surface markers and more particularly to markers adapted to be used as center lines and lane lines on highways.

Prior to the instant invention, it has been customary to simply paint center lines and lane lines on highways but such lines have been found to be relatively short-lived; and necessary, very frequent replacement has been relatively costly. Further, the reflecting efficiency of these lines at night has not been high enough to give satisfactory results.

It has been proposed that glass spheres be incorporated in these painted lines while they were in a moist condition in order to increase the reflecting efficiency of the lines at night. While such lines have been somewhat better than the lines comprising simply paint, yet the lines incorporating glass spheres have not been very much longer lived for the glass spheres soon become detached from the paint and the line wears away by traffic as before.

It is an object of the instant invention to provide a marker suitable for use as a center line, lane line, or vertical surface sign which will be relatively strong and long lived and comprise a binding material, auto-collimating units and a filling material associated with each other in a novel manner.

Other objects and the nature and advantages of the invention will be apparent from the following description taken in conjunction with the accompanying drawing, wherein:

Fig. 1 is a view in perspective taken at night time of a highway including surface markers in accordance with the invention;

Fig. 2 is a fragmentary sectional view taken along line 2—2 of Fig. 1 at one stage of the application process;

Fig. 3 is a view similar to Fig. 2 taken subsequently at a time when the reflecting film has dried; and

Fig. 4 is a view similar to Fig. 3 taken later in the process illustrating an additional filling and strengthening film.

Referring to the drawing, a road 20 has applied thereto a center line 21 and at its side is erected a vertical marker 22. The center line 21 is fabricated as described below.

It has been found in practice that when auto-collimating units such as glass spheres depend for their support against dislodgement entirely upon the pigmented binder which is necessary in order that the units have the proper reflecting properties, optimum wear conditions do not result. Prior attempts to increase the binding

efficiency of the pigmented paint have resulted in the selection of binders which have an affinity for the material of the auto-collimating units, thereby effecting a "climbing up" about or a cupping of the units by the binder.

This thickness of the films which climb up about the auto-collimating units is but little and is readily broken off by traffic.

In the laying of the marker in accordance with the invention, a reflecting binder 23 is applied to the road surface or other surface to be marked and while the binder is in a wet or semi-wet condition, the autocollimating units 24, which may be glass spheres or other units such as specified in the Gill Patent No. 1,902,440, are incorporated therein by a dispensing machine or by hand in a manner to effect either a chance distribution or a distribution in accordance with a predetermined plan as desired. When the reflecting binder 23 has dried, a section of the marker may appear as illustrated in Fig. 3, each of the units 24 being held in place by the gripping portions 25 in between which the binder 23 has shrunk to its dry film thickness 26, leaving the gripping portions 25 relatively weak and unsupported though contacting the auto-collimating units over a relatively large area.

A clear filler 27 is then applied to the dry section illustrated in Fig. 3 to fill the cavities therein, which filler may have little or no affinity for the auto-collimating units 25 but more or less marked affinity for the binder 23, whereby a relatively strong composite binder 23, 27, is effected. The reflecting binder 23 is preferably of a nature corresponding to that taught in copending application Serial Number 274,666 and the filler 27 which may be clear or relatively clear may have a formula similar to that of the binder 23, or the same formula as the binder 23 minus pigment. While the reflecting binder may have a greater difference in thickness between its wet film and dry film due to dissipation of the vehicle in which the pigment is suspended, the filler 27 which may be clear, sans pigment, may have substantially the same thickness under wet and dry conditions as determined by the formula selected in accordance with the teachings in copending application Serial Number 274,666.

A reflecting marker laid in accordance with the above process is inherently strong, capable of long life, and because of the utilization of a minimum of pigment, its cost is relatively low.

It is to be understood that it is within the scope of the invention to fabricate vertical markers such as the sign 22 as well as horizontal

markers such as the center or lane line 21 and that the auto-collimating units may be graduated in size from say 0.005 to 0.040 inch in diameter.

It will be obvious to those skilled in the art that various changes may be made in this device without departing from the spirit of the invention and therefore the invention is not limited to what is shown in the drawing and described in the specification but only as indicated in the appended claims.

What is claimed is:

1. A combined surface marker comprising a road surface, a reflecting pigmented binder on said surface, a plurality of autocollimating units ranging in size from .005" to .040" at least partially embedded in said binder and partially exposed with the binder gripping said units in cup-like formation and having valleys between said cup-like formations, and a protecting film extending over said binder in said valleys and to a

height approximating the height of said cup-like formations, whereby said surface marker will have the properties of great durability and resistance to traffic shock.

- 5 2. A combined surface marker comprising a road surface, a reflecting pigmented binder on said surface, a plurality of relatively small autocollimating units partially embedded in said binder and partially exposed with the binder
10 gripping each of said units in upwardly extending wall formations and said binder having valleys on its upper surface between said upwardly extending wall formations, and a protecting film extending over said binder in said valleys and
15 to a height approximately the height of said upwardly extending wall formations, whereby said surface marker will have the properties of great durability and resistance to shock.
